United States Patent Office

Des. 184,515
Patented Mar. 3, 1959

184,515

PLANTER OR THE LIKE

Thomas L. Fawick, Cleveland, Ohio

Application May 15, 1957, Serial No. 46,178

Term of patent 14 years

(Cl. D35—3)

Fig. 1 is a perspective view of a planter or the like showing my new design.

Fig. 2 is a side elevation of the same.

Fig. 3 is an end elevation of the same.

Fig. 4 is a bottom plan view of the planter.

I claim:

The ornamental design for a planter or the like, as shown.
